UNITED STATES PATENT OFFICE.

JAMES H. ALDEN, OF WAHOO, NEBRASKA.

PRICE MARKER.

Application filed March 17, 1927. Serial No. 176,184.

My invention relates to markers for cards and tags and more specifically to devices for marking prices on cards and tags which are to be applied either directly to the goods or their containers or to the shelves or counters on which the goods are displayed.

One object of my invention is the provision of a simple price marker of the utmost convenience, with type bars always in position where they may be easily selected for impressing their indicia on the card or tag.

Another of my objects is the provision of attaching means for the type bars whereby it is impossible to misplace the type bars and whereby the type bars may be selectively used without interference from the other type bars.

Another of my objects is the provision of an adjustable device for receiving and for centering a card or tag, this device being combined with another adjustable device for guiding the type bars in a manner such that the characters will be applied to the card so as to be symmetrical with respect to the outline of the card.

Having in view these objects and others which will be pointed out in the following description, I will now refer to the drawings, in which

Figure 1 is a perspective view of my price marker in its preferred form.

Figure 2 is a view in perspective of the base of the gauge.

Figure 3 is a perspective view of the adjustable spacer.

Figure 4 is a view in perspective of the adjustable stop.

Figure 5 is a view in perspective of one of the keys or hammers.

Figure 5^A is a plan view of the bottom surface of the key or hammer shown in Figure 5.

Figure 6 is an illustration of a type guide of somewhat modified form.

The frame of the device includes a base 10 having two end walls 11. Two rods 12 are secured in the end walls 11 so as to span the distance between the end walls, the two rods being in parallel relation. Secured to the rods 12 are keys or hammers 13, half of the hammers being on one rod and the other half on the other rod. In one end of the base 10 is a sunken stamp pad 14 which is so positioned that all of the hammers 13 may rest on the stamp pad when not being used.

The individual hammer is shown in Figures 5 and 5^A. These hammers are each provided with an aperture 15 for receiving a rod 12 in such a way that the hammers will be slidably and pivotally secured to the rod. At the upper portion of each hammer is a head 16 which is so shaped that it may be conveniently grasped by the fingers. At its base the hammer is notched for receiving type bars 17 having suitable indicia thereon. In my preferred construction I employ interchangeable rubber type. It is understood, of course, that the parts of the hammers 13 are so proportioned that all of the type bars 17 will be in alignment when they rest on the surface of the base 10.

The guide shown in Figure 1 includes a base 18 which is secured to the base 10, the base 18 being provided with an aperture 19. The base 18 is spaced slightly from the base 10 and it is provided with outturned flanges 19' from its upper surface at two of the opposite edges of the aperture 19. The slide 20^b in Figure 3 is so arranged that it is engageable with the flanges 19' so as to be slidable thereon. The slide is provided at its forward end with an upstanding tongue 21 for convenience in grasping it. The slide 20 is also provided with two apertures 22 and 23 each of the apertures having a plurality of wires or rods 24 extending lengthwise thereof. If only three characters are to be placed on the price tag, the slide 20 is positioned so as to bring the aperture 22 in alignment with the type bars 17 and if four characters are desired, the adjustment of the slide 20 is so made as to bring the aperture 23 into the proper alignment. The hammers 13 are slidably moved on their rods 12 and the selected hammers are then pressed down between the wires 24 so as to properly space the characters on the tag. The apertures 22 and 23 are transversely symmetrical on the slide 20 so that when the price tag 25 is inserted the characters will be properly spaced with reference to the lateral edges of the card 25.

It is frequently desired to produce a number of price tags having different characters but in all of which the characters are uniformly spaced with reference to all edges of the tag. The price tag 25 is inserted at one end of the base 18 and in my device I provide an adjustable stop 26 as best shown in Figure 4. This stop has a stop edge 27 and a depending tongue 28 for grasping it be-

tween the thumb and forefinger to force it forwardly or rearwardly. The stop 26 is slidably secured between the bases 10 and 18.

In Figure 6 I have shown a modified gauge of somewhat simpler form. The strip 29 is secured in spaced relation to the base 30 which corresponds to the base 10 of the preferred construction. The strip 29 is spaced from the base 30 by means of spacers as shown in dotted lines, which construction permits sliding the price tags underneath the strip 29 so as to be symmetrical with respect to the notches 31 and 32. The notch 31 is sufficiently wide for three characters, while the notch 32 is wide enough for four characters. Either a fixed or adjustable stop 33 may be employed in connection with the modified form of gauge as shown in Figure 6.

Having thus described my invention in such full, clear, and exact terms that its construction and operation will be readily understood by others skilled in the art to which

it pertains, what I claim as new and desire to secure by Letters Patent of the United States is:—

1. A price marker having a base, a rod secured to said base in spaced relation therewith, a plurality of type bars pivotally and slidably mounted on said rod, an inking pad secured to said base, and a spacing device on said base for receiving the card or tag to be printed and having means for symmetrically spacing the characters from said type bars on the card or tag. 35

2. A price marker having a base, a rod secured to said base in spaced relation therewith, a plurality of type bars pivotally and slidably mounted on said rod, an inking pad secured to said base, an adjustable spacing device for receiving the cards or tags to be printed, and having adjustable means for symmetrically spacing the characters from said type bars on the card or tag. 40

In testimony whereof I affix my signature.
JAMES H. ALDEN.
